UNITED STATES PATENT OFFICE.

GEORG SPIESS, OF LEIPZIG, GERMANY.

RELEASING DEVICE FOR THE COMBING-WHEELS IN SHEET-FEEDERS.

1,192,011.

Specification of Letters Patent. Patented July 25, 1916.

Application filed June 25, 1915. Serial No. 36,174.

To all whom it may concern:

Be it known that I, GEORG SPIESS, a citizen of the German Empire, and a resident of Leipzig, Germany, have invented certain new and useful Improvements in Releasing Devices for the Combing-Wheels in Sheet-Feeders, of which the following is a specification.

This invention has reference to a novel 10 releasing device for the combing wheels in sheet feeders.

In the usual sheet feeders, that is the machines which serve for separating single sheets of paper from a bank of sheets and 15 transport them farther, there is provided a special device to raise from the table the combing wheels which transfer the single sheets, and a special device for advancing the bank of sheets. Both movements are 20 brought into certain relations to each other and the release of the combing wheels must take place, at the moment, when a sheet with its front edge, while entering between the transporting rolls, actuates a finger. 25 The weak force of the edge of the sheet of paper, even if said sheet is thin, must be utilized for initiating the raising of the combing wheel which must be effected as free from vibration as possible, because the 30 sheet feeder works with exceedingly high speed.

According to the present invention, the catch which is influenced by the finger is linked to a movably mounted bar which 35 affects the movement of the press lever that checks the releasing device for the combing wheels when ascending.

The invention is illustrated in the accompanying drawing in which:

40 Figure 1 represents in front view a releasing device for the combing wheels in sheet feeders embodying in desirable form the present improvements. Fig. 2 is a similar view showing the operative mechanism 45 in a different position with the bank of sheets partly cut away.

In the machine herein described two or 50 more combing wheels are employed and a corresponding number of sheet feeders. 55 For convenience sake the construction and operation of a single combing wheel will be described in detail. Fig. 3 is a plan view of the releasing device.

In the releasing device illustrated the 55 combing wheel A is mounted on the swing arm B in the usual manner so that the

combing wheel remains active in every position. The swing arm B may perform an ascending or descending motion by means of an angular lever C. This angular lever rests with its outer end portion D upon a spring actuated bar F. The spring G tends to keep the bar F in its highest position and the combing wheel A then is also in its raised position so that it has no effect on the transfer of the wheel. The bar F is checked by two pins H—I which serve as brake cheeks. These pins are secured to an angular lever K which has a pivotal point at L and is held in its highest position 70 by a spring M.

The operation of the angular lever K, according to the present invention, is effected by means of a bar N which bears, with its free outer end, against the free 75 bottom end of the angular lever K. A catch C is movably suspended from the bar N and is kept in readiness for work by means of a swing arm P, which is movably mounted upon a shaft carrying the 80 finger Q. The weight of the finger Q causes the swing arm P to press said swing arm in a downward direction. The free end of the swing arm P then rests against the notch of the member R of the catch O when 85 the comber falls, which notch forms an extension of the catch beyond the pivotal point. The catch O is purposed to engage the teeth of a movable tooth rack S and is kept out of engagement with the rack until 90 the finger actuated by the passing sheet is raised. When the tooth rack S is checked it effects the releasing of the combing wheel A in the known manner and also influences the transfer of the bank of sheets. 95

For actuating the transport roll V of the feathered bank of sheets a pawl and ratchet mechanism is provided adjoining said roller V. This mechanism consists of a ratchet W and a pawl X adapted to drive the ratchet, 100 said pawl being linked to a swing arm Y. By means of gears the movement of the pawl and ratchet mechanism is transmitted to the transport roll V.

The swing arm Y receives its motion 105 from the crank pin Z¹ which is mounted on a crank disk Z². The motion of the crank pin is transmitted upon a swing arm 1 by means of the crank rod Z in peculiar manner. The swing arm 1 carries 110 a pin 2 which is located within a slot 3 formed in the enlarged end of the crank rod

C. The connection between these parts is assured by means of the spring 4 which tends to draw the whole swing arm 1 toward the crank rod Z. A rod 5 is linked to the swing arm 1 which rod is attached to the swing arm Y of the pawl and ratchet mechanism. In this manner the turning movement of the crank Z¹ is transmitted, by the described intermediary elements, to the transport roll V. The movement of the swing arm 1, however, is limited by means of the tooth rack S which is provided with a pin 6 that reaches into a slot 7 of the swing arm 1. If the tooth rack S is suddenly stopped then the crank Z¹ may continue its movement toward the left but the swing arm 1 and, as a consequence, the swing arm Y do not perform this movement. The movement of the tooth rack S which is carried along by the swing arm 1 may now be limited by means of the catch O which engages the teeth of the rack. If now the finger Q is actuated by the front edge of a passing sheet then the swing arm P releases the catch O which now engages the teeth of the rack S, as shown in Fig. 2, whereby the motion of the tooth rack S is next transmitted to the bar N and from this bar to the angular lever or bar K. The bar K now brings the stop pins H—I into another location whereby the clamping of the bar F is released which bar then ascends under the action of the spring G and takes along the angular lever C. The lever C, in turn, moves the lever B of the combing wheel A whereby the combing wheel A is raised from the sheet. The bar F further has a pin U which acts on an auxiliary arm T of the finger Q and moves said arm upward whereby the finger Q also is raised beyond the sheet of paper.

According to the period of time when the front edge of the top sheet of paper raises the finger Q sooner or later, the swing arm 1 and the swing arm Y will be limited in their respective positions sooner or later relative to their positions to the crank rod Z. For each revolution of the crank the time of the release of the combing wheel and also the time for advancing the bank of sheets is regulated so that both movements are harmonized. At the end of each completed revolution of the crank Z¹ all the other elements are returned into their initial positions by well known intermediary elements.

As stated the bar F is raised by the spring G and takes along the lever C. The bar F is returned into its initial position during each revolution of the crank Z¹. This is effected by means of the curve disk 11 mounted upon

the shaft 10 of the crank disk Z². Upon the 60 surface of the curve disk 11 there is a nose 12 which during the rotation of this disk reaches the pin 13 mounted upon the bar F. At the end of one revolution of the curve disk 11 its nose 12 presses upon the pin 13 65 and returns the bar F into its lowest position in which it is held by the pins H, I, and all the other members have been returned into their initial position.

I claim as my invention:

1. A releasing device for the combing wheels in sheet feeders comprising a finger adapted to be operated by the front edge of a passing sheet, a catch actuated by said finger, a bar to which said catch is pivoted, 75 and a brake lever actuated by said bar.

2. A releasing device for the combing wheels in sheet feeders comprising a finger adapted to be operated by the front edge of a passing sheet, a catch actuated by said finger, a movable tooth rack adapted to be limited in its movement, a bar to which said catch is pivoted, and a brake lever actuated by said bar.

3. A releasing device for the combing wheels in sheet feeders comprising a finger adapted to be operated by the front edge of a passing sheet, a swing arm supporting the finger, a catch actuated by said finger and swing arm, a movable tooth rack adapted 90 to receive periodically the catch to limit its movement, a bar to which said catch is pivoted, and a brake lever actuated by said bar.

4. A releasing device for the combing wheels in sheet feeders comprising a finger 95 adapted to be operated by the front edge of a passing sheet, a catch actuated by said finger, a bar to which said catch is pivoted, a brake lever actuated by said bar, and means in connection with said brake lever to release the combing wheels.

5. A releasing device for combing wheels in sheet feeders comprising a finger adapted to be operated by the front edge of a passing sheet, a catch actuated by said finger, a bar 105 to which said catch is pivoted, a brake lever actuated by said bar, means in connection with said brake lever to release the combing wheels, and means for advancing the bank 110 of sheets to bring the top sheets successively underneath the said combing wheels.

Signed at Leipzig, Germany, this 4th day of May, 1915.

GEORG SPIESS.
